CLAIM

The ornamental design for a disposable heel blood collecting device, as shown and described.

DESCRIPTION

FIG. 1 is a Perspective View of a disposable heel blood collecting device showing my new design;

FIG. 2 is a Perspective View thereof;

FIG. 3 is a Front View thereof;

FIG. 4 is a Rear View thereof;

FIG. 5 is a Left Side View thereof;

FIG. 6 is a Right Side View thereof;

FIG. 7 is a Top View thereof;

FIG. 8 is a Bottom View thereof;

FIG. 9 is an enlarged view of the portion of FIG. 5 encircled by a dot-dah line and labelled "9";

FIG. 10 is an enlarged view of the portion of FIG. 5 encircled by a dot-dah line and labelled "10";

FIG. 11 is an enlarged view of the portion of FIG. 6 encircled by a dot-dah line and labelled "11";

FIG. 12 is an enlarged view of the portion of FIG. 6 encircled by a dot-dah line and labelled "12"; and,

FIG. 13 is an enlarged view of the portion of FIG. 7 encircled by a dot-dah line and labelled "13".

The dot-dash broken lines encircling portions of the views shown in FIGS. 5, 6, and 7 indicate portions of the design shown in the enlarged views of FIGS. 9, 10, 11, 12 and 13. The dot-dash broken lines form no part of the claimed design.

The broken lines shown in FIGS. 1-4 and 8-13 illustrate portions of the disposable heel blood collecting device that form no part of the claimed design.
